UNITED STATES PATENT OFFICE.

MOE JACOB, OF NEW YORK, N. Y.

SHOE.

Application filed July 21, 1925. Serial No. 44,997.

To all whom it may concern:

Be it known that I, MOE JACOB, a citizen of the United States, residing at New York, in the county of New York and State 5 of New York, have invented certain new and useful Improvements in Shoes, of which the following is a specification.

This invention relates to the art of making shoes and more particularly to the 10 mode of cutting the material from which the shoes are formed.

The principal object of the invention is to enable the entire upper including the tongue vamp and quarters to be cut from 15 one piece or blank without waste of material.

Another object of the invention is to have the ankle cut-out used as the tongue.

Still another object of the invention is 20 to reduce the cost of production by lessening the waste of material and the labor required in the manufacture and at the same time render the shoe more easy and comfortable to wear and increase its wearing 25 qualities.

Other objects will appear as the disclosure progresses. The drawings are intended merely to indicate a possible embodiment of the invention. It is obvious therefore, 30 that the actual needs of manufacture may necessitate certain mechanical changes. It is therefore not intended to limit the invention to the embodiment illustrated, but rather to define such limits in the appended 35 claim.

For a more detailed understanding of the invention, attention is now called to the drawings in which a preferred embodiment

is shown. In these drawings like parts are designated by like reference characters in 40 all the views.

Fig. 1 is a plan view or pattern of a single piece of leather forming what may be termed the vamp, the quarters and the 45 tongue of the shoe.

Fig. 2 is a top plan view of a completed shoe showing the tongue stitched in place.

Fig. 3 is a side view of the completed shoe.

Fig. 4 is a detached view of the tongue. 50

Referring now to the drawings in detail, numeral 1 designates a blank form of material from which the shoe is formed, numeral 2 the vamp, numeral 3 the quarters and numeral 4 a straight slit. Between 55 the quarters a piece of material 5 is removed to form the ankle opening, the said piece being later used as the tongue of the shoe and stitched to the vamp by stitches 6 as shown in Figs. 2 and 3. 60

Having thus described my invention, what I desire to secure by United States Letters Patent is:

A method of forming the complete upper of a shoe including the tongue which 65 consists in cutting the material to form the body of the shoe upper and cutting from the said body an ankle opening and a slit extending forwardly from said ankle opening and then attaching the piece cut out 70 to form the said ankle opening adjacent said slit to form a tongue.

In testimony whereof I affix my signature.

MOE JACOB.
